UNITED STATES PATENT OFFICE.

DE BERT HARTLEY, OF CHICAGO, ILLINOIS.

DESIGN FOR A COMBINED DRESSER AND COMMODE.

SPECIFICATION forming part of Design No. 30,394, dated March 28, 1899.

Application filed February 16, 1899. Serial No. 705,725. Term of patent 7 years.

To all whom it may concern:

Be it known that I, DE BERT HARTLEY, a citizen of the United States, residing at Chicago, Cook county, State of Illinois, have invented and produced a new and original Design for a Combined Dresser and Commode, of which the following is a specification, and which is illustrated in the accompanying drawings, forming a part of this application, in which—

Figure 1 is a front elevation of my design, and Fig. 2 is a plan view with the top removed.

As shown in the drawings, my design resembles in its general outline a dresser, upon which is mounted a mirror *a*, supported by standards *a'* on either side thereof. The frame or body part of my design has parallel sides or ends *b*, which are connected at the back by portions *c*, at the front by a bar *d*, and at the top by a cover *e*. Extending from the front edge of the cover *e* is an upright piece *f*, the outer edge of which has a curved line or contour. The central portion of the design consists of an upright *g*, which occupies most of the space between the side *b*, the bottom *d*, and the top *e*. Extending

from the portion *g* are shelves *h i*, the latter being near the bottom of the device, and connecting the shelves *h i* is a vertical post *j*. Extending upwardly from the shelf *h* are small posts *k*, from the upper ends of which extend rods *a'*. Extending at right angles from the portion *g*, about half-way between the shelves *h* and *i*, are horizontal brackets *i*. Extending rearwardly from the portion *g* is a section *m*, having its outer face curved as shown. In the angles formed by the junction of the sides *b* and the back pieces *c* are triangular-shaped horizontal shelves *n*. Extending forwardly and in an outward curve is a small rod *o* at a slight distance above the shelf *i*.

Having thus described my invention, what I claim is—

The design for a combined dresser and commode, substantially as herein shown and described.

In testimony whereof I affix my signature in presence of two witnesses.

DE BERT HARTLEY.
